Primary Examiner—Freda Nunn

(74) *Attorney, Agent, or Firm*—Beyer Weaver & Thomas, LLP

(57) **CLAIM**

We claim the ornamental design for a computer, substantially as shown and described.

DESCRIPTION

FIG. 1 is a perspective view of a computer in accordance with the present design;
FIG. 2 is front view for the computer as shown in FIG. 1;
FIG. 3 is a rear view for the computer as shown in FIG. 1;
FIG. 4 is a right side view for the computer as shown in FIG. 1;
FIG. 5 is a left side view for the computer as shown in FIG. 1;
FIG. 6 is a top view for the computer as shown in FIG. 1; and,
FIG. 7 is a bottom view for the computer as shown in FIG. 1.
The broken lines are shown in the views for illustrative purposes only and form no part of the claimed design.

1 Claim, 4 Drawing Sheets
